Inventor:

G. W. Woodworth

UNITED STATES PATENT OFFICE.

GEORGE W. WOODWORTH, OF CLEVELAND, OHIO.

WATER-ELEVATOR.

Specification of Letters Patent No. 36,318, dated August 26, 1862.

To all whom it may concern:

Be it known that I, GEO. W. WOODWORTH, of Cleveland, in the county of Cuyahoga and State of Ohio, have invented a new and 5 Improved Wheel or Pulley for Water-Drawers; and I do hereby declare that the following is a full and exact description thereof, reference being had to the accompanying drawings, and to the letters of reference 10 marked thereon, making part of this specification, in which—

Figure 1 is a side view of my improved wheel. Fig. 2 is a sectional view through the center, edge wise. Fig. 3 is a section of 15 the wheel or pulley with the chain passing over the same.

Figs. 1, and 2, show a forked wheel for the use of a chain or rope constructed different from the common forked wheel now in use. 20 The tops or points of the forks are connected by means of a bar or rod of the same material, running from the outer ends or points of one fork to the next in position, thereby forming a complete circle on both 25 sides of the wheel between which the rope or chain passes into the forks, thereby preventing the forks from breaking as in common forked wheels.

Figs. 2, and 3, show the construction of the bottom of the forks. A in Figs. 2 and 3 30 shows a flat place in the bottom of the forks, upon which the edge of the link rest, being held by the forks.

B, in Figs. 1 and 3 shows an inverted arch or section of a circle between the forks which 35 adds strength and comeliness to the forks, and also prevents the collection of dirt or ice in the bottom of the forks.

It will be seen from the above description, that I construct a very substantial and hand- 40 some wheel.

Now I do not claim the forked wheel or open bottom wheel or pulley. But

What I do claim and desire to secure by 45 Letters Patent, is—

The combination of the flat places A and inverted arch or section of a circle B with the base forming the perimeter which connects the forks as above described.

GEO. W. WOODWORTH.
